UNITED STATES PATENT OFFICE

JOHN R. HUME, OF CHICAGO, ILLINOIS

FOUNTAIN PEN

Application filed May 23, 1924. Serial No. 715,275.

My invention relates to a fountain pen and has for its object to provide an improved and efficient device of this type.

Fig. 1 is a view of my invention with a part of the closing cap broken away;

Fig. 2 is a longitudinal sectional view taken on line 2—2 of Fig. 1;

Fig. 3 is an enlarged cross sectional view taken on line 3—3 of Fig. 2, and

Fig. 4 is an enlarged cross sectional view taken on line 4—4 of Fig. 2.

The preferred form of my fountain pen comprises a tubular member or shell 8 with an intermediate cross partition 9 dividing the interior of the shell into two cylindrical chambers extending from said partition in opposite directions to the two opposite ends of the tubular shell. A knurled cap 10 is removably threaded on one end of the shell and a sleeve 11 with a reduced portion 11' is removably threaded in said cap and carries a pen 13, an ink feeding channel 12 being provided through said reduced portion. An ink tube 14, preferably of glass, is mounted in shell 8 and contains an upper flange 15 resting on the upper edge of said shell and provided with a finger lug 16 which is bevelled at its outer edge to be engaged by the finger nail for withdrawing the ink tube from the shell. A pliable gasket or sealing member 17 is interposed between flange 15 on the ink tube and the inner part of cap 10 to provide a fluid-tight connection.

Preferably, the device further includes a cap 20 threaded on the other end of shell 8 and provided with a conical portion or extension 21 having interior threads 22 and in which operates a stem 23 provided with one or more thread means or lugs 24 movable in said threads 22 for pushing the lead 25 outward in portion 21. The stem is provided with a head 26 for operating the stem, and said head and the upper portion of said stem are movable in a sleeve 27 which is fastened in the shell, preferably with webs 27' as shown in Fig. 4, and provides a storage chamber 28 between itself and the inner wall of said shell for storing additional leads 29, as shown also in Fig. 4. The caps 10 and 20, and the sleeve

11 and head 26 are roughened or knurled to provide a firm grasp for the fingers.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having described my invention, what I claim as new and desire to secure by Letters Patent is:

In a device of the class described, comprising a shell having a pen chamber, a screw cap bearing a pen point and provided with an ink channel removably mounted on the open end of said pen chamber, the combination therewith of a rigid removable ink tube, open at one end and adapted to be contained in said pen chamber, said ink tube provided with an out turned flange around its open end overlaying the open end of said pen chamber and held in place by said cap, and a beveled finger lug integral with said flange, substantially as described.

In testimony whereof I have signed my name to this specification.

JOHN R. HUME.
